UNITED STATES PATENT OFFICE.

JOHN WRIGHT AND JOHN WILLIAM MITCHELL, OF MOSGIEL, NEW
ZEALAND.

HAT-FASTENER.

SPECIFICATION forming part of Letters Patent No. 631,916, dated August 29, 1899.

Application filed July 15, 1898. Serial No. 686,035. (No model.)

To all whom it may concern:

Be it known that we, JOHN WRIGHT and JOHN WILLIAM MITCHELL, subjects of the Queen of Great Britain, and residents of the 5 borough of Mosgiel, (Otago,) in the Colony of New Zealand, have invented an Improved Fastener for Hats and the Like, of which the following is a specification.

This invention relates to fasteners used for 10 securing hats, bonnets, and the like upon the head of the wearer; and the object of the invention is to provide a fastener which may be ornamental and by which a hat or the like may be effectually secured without damaging 15 the same.

The usual manner at present in vogue for fastening hats is to pass a long pin or pins through any suitable raised part of the hat and through the hair of the wearer. Such 20 pins catch a small quantity of the hair only; but by my invention a considerable quantity of hair is caught and utilized, with the result that a better hold is obtained for securing the hat.

25 The invention is carried into effect in the case of a hat by attaching combs to the ends of wires passed through the sides of the hat. The combs are drawn together by means of springs made, preferably, of elastic webbing, 30 india-rubber, or the like. A frame or loops connect the springs to the hat to hold the same down upon the head. The outer ends 35 of the wires may be provided with any suitable ornaments, such as knobs, monograms, or the like.

In attaching a hat the wires, with their 40 combs, are withdrawn sufficiently to separate the combs. The wires are then elevated in order to depress the combs, when the teeth will enter the hair and hold the hat down to 45 the head of the wearer upon the wires being released.

In order that our invention may be most easily understood, reference will be made to 45 the accompanying drawings, on which—

Figure 1 is a detail sectional view. Fig. 2 is a view at right angles to Fig. 1. Fig. 3 is a plan view of the frame. Fig. 4 is a sectional view showing the invention applied to a hat.

50 Similar letters indicate corresponding parts.

The wires a pass through the sides of the hat and have knobs a' , their inner ends being screw-threaded at a'' . Combs b are mounted upon the wires a'' , the bosses b' , secured to the back of the combs, being pierced and screw-threaded to receive the wires a'' . The combs are thus adjustable upon the wires, and their distance apart may be regulated to allow the teeth to overlap more or less. (See Fig. 4.) A frame c is attached to the interior of the 60 hat c' , as hereinafter described, and has loops c^2 in cross-bars c^3 , to which one end of springs c^4 , of elastic, are secured. The other ends of the springs are attached to the combs.

To secure the hat, the knobs a' are pulled 65 out and the combs separated to the position shown by Fig. 4. The hat is then placed upon the head of the wearer and the knobs gently released and allowed to grip into the hair and thus secure the hat. 70

The drawings show a cheap and light form of frame which may be readily secured within a hat, in which the sides c^5 and c^6 slide one within loops formed upon the other and have a spring c^7 in tension passed through the 75 loops c^8 . The ends c^9 of the sides are bent, as shown, and pointed at c^{10} . This form of frame is sprung into the hat when it is held securely by the spring c^7 , or the combs may have any suitable form which will effectually grip a 80 quantity of hair to securely hold the hat or the like.

Having now particularly described and ascertained the nature of our said invention and in what manner the same is to be performed, we declare that what we claim is— 85

In combination, the comb, the elastic connection between the same and the frame and the frame comprising the sides c^5 c^6 sliding one on the other, the spring c^7 and the pointed 90 ends c^{10} gripping the hat, substantially as described.

In witness whereof we have hereunto set our hands in presence of two witnesses.

JOHN WRIGHT.
JOHN WILLIAM MITCHELL.
